(21) Appl. No.: **29/411,305**

(57) CLAIM

(22) Filed: **Jan. 19, 2012**

The ornamental design for a flower over the cabinet/drawer hanger support for household items, as shown and described.

Related U.S. Application Data

(63) Continuation-in-part of application No. 29/341,400, filed on Aug. 5, 2009, now Pat. No. Des. 654,705.

DESCRIPTION

(51) **LOC (9) Cl. 06-08**

FIG. 1 is a perspective view of a flower over the cabinet/drawer hanger support for household items showing our new design;

(52) **U.S. Cl.**

FIG. 2 is a top plan view thereof;

USPC **D6/323**

FIG. 3 is a front elevational view thereof;

(58) **Field of Classification Search**

FIG. 4 is a bottom plan view thereof;

USPC D6/315-328; D8/349, 354, 356, 359,

D8/367, 371, 372, 376, 380; 211/1, 13.1,

211/85.3, 87, 106, 119, 183; 223/85-98;

40/322; 248/75, 89, 251, 302

See application file for complete search history.

FIG. 5 is a rear elevational view thereof;

(56) **References Cited**

FIG. 6 is a right side elevational view thereof, the left side elevational view being a mirror image;

U.S. PATENT DOCUMENTS

FIG. 7 is a perspective view of the flower over the cabinet/drawer hanger support for household items shown in an alternate environment;
